UNITED STATES PATENT OFFICE.

HOMER P. CHANDLER, OF MANSFIELD, OHIO, ASSIGNOR TO THE OHIO BRASS COMPANY,
OF MANSFIELD, OHIO, A CORPORATION OF NEW JERSEY.

TROLLEY HEAD.

Application filed August 23, 1927. Serial No. 214,847.

My invention relates to trolley heads and particularly to that type known as alining heads.

The object of my invention is to provide a head in which the portion which supports the trolley wheel or collector may swivel with respect to the pole as the car moves out of alinement with the trolley wire, and also to provide means for tending to maintain the alinement of the trolley wheel with respect to the pole.

A further object is to provide a large area of contact between the relatively movable parts.

In the drawing accompanying this specification:

Fig. 1 is a side view of my trolley head in partial section to show the swivel parts, and it is also shown as mounted upon the end of a pole.

Fig. 2 is a sectional view on the line 2—2 of Fig. 1.

In the preferred embodiment of my invention I employ a pole casting or member 1 which is arranged to be secured to the end of the trolley pole or other support 2 by means of the bolt and washer 3. There are various types of connections between the members 1 and 2 which may be used, but the one shown will provide a practical connection.

Mounted upon the upper end of the pole casting 1 is a hollow member 4 having a side opening 5 and the top and bottom openings 6 and 7 respectively. The member 4 has a flat surface or top, although this surface may be curved if desired. The cross section of the member 4 is cylindrical. This permits the collector support 8 to be mounted upon the member 4 and rotate relative thereto. The collector support 8 comprises an inverted cup-shaped member 9, the inner surface of which fits the outer surface of the member 4 and makes good contact therewith. This gives a large area of contact between the parts, which reduces the current per square inch which these surfaces must carry, and avoids the necessity of using a flexible copper connection between the members 1 and 8. Where the contact between members corresponding to the members 1 and 8 is small and the current carrying large per unit area contact, it is found

that there is very likely to be considerable pitting of the movable surfaces. 55

Mounted within the hollow member 4 is a helical spring 10, the ends 11 of which project laterally therefrom and engage the edges of the opening 5. The member 9 is also provided with an opening 12 and the edges of this opening also may engage the ends 11 of the spring. The member 8 is provided with an opening 13, which registers with the openings 6 and 7, and mounted within these openings is a bolt or axle 14, which maintains the parts against separation longitudinally. 65

The openings 5 and 12 register with each other and the spring 10 maintains the openings in alinement when the device is operating under normal conditions, that is, when the trolley wire is directly over the pole and trolley head and extends in the direction of travel of the car. 70

Mounted upon the member 9 are spaced 75 arms 15, one on each side of the current collector 16, and the upper ends of which are connected by the axle 17, held in place by the spring cotter 18.

The member 4 is mounted at such an angle 80 with respect to the axis of the pole 2 that under normal operating conditions the vertical axis of the members 4 and 14 will substantially at all times be in a vertical position. The upward pressure of the pole 85 2, which is brought about by means of a spring operated trolley base tends to maintain contact between the surfaces of the parts 4 and 9 when the current collector engages a trolley wire, and, therefore, it is not necessary to draw the nut 19 very tight. 90

My improved head will permit the car to round a curve and the groove in the current collector maintain its alinement with the trolley wire while rounding the curve and reduce 95 friction and wear between the collector 16 and the trolley wire, and the spring 10 is biased to move the members 1 and 8 into and yieldingly maintain the members in alinement when the car is moving on a straight 100 track.

If the spring ends do not normally engage both edges of both hollow member openings 5 and 12, the device is still practical, but there will be a small rotative movement 105 of the members from normal, that is, when

the car is moving in alinement with the trolley wire, which will not be restrained by the spring and this movement will amount to the difference in the width of the openings 5 and 12.

5 The members 4 and 9 inter-engage to prevent lateral displacement and if the collecting device did not at times leave the wire while moving relative thereto, it would not be necessary to use the axle bolt 14 as the upward pressure of the pole would at all times maintain the parts against longitudinal displacement while in use.

10 There are modifications which one skilled in the art will readily understand from my disclosure, but I wish to be limited only by my claims.

15 I claim:

1. A trolley head comprising a pole casting having a hollow projecting member therefrom with a side opening and two vertical central openings, a harp member having spaced parts to support a collector and a hollow projecting member therefrom with 20 a side opening and a bottom opening and arranged to receive the first said hollow projecting member and a top opening to register with the said vertical central openings, means passing through the registering openings to hold the said parts together in 25 rotative relation, a helical spring mounted in

the first said projecting member with its ends projecting laterally and engaging the edges of the walls forming the side openings in the said parts and adapted to yieldingly hold the pole casting and the harp member in predetermined relation.

2. A trolley head comprising a pole casting having a hollow member with smooth exterior side walls of circular formation, a 40 side opening and a spring mounted in the hollow member and its ends engaging the side walls of the openings, the hollow member having a flat top with a hole through the top to receive an axle, a harp member having spaced arms to receive a current collector and having an inverted cup-shaped member to fit over the said hollow member and have its interior side walls contact with the exterior side walls of the hollow member and 45 the exterior flat surface of the hollow member engaging with the inner top surface of the inverted member, a side opening to the inverted member and the walls of which engage with the ends of the spring 50 biased to return the parts to their normal predetermined relative position and an opening in the inverted member to receive the axle.

55 In testimony whereof I affix my signature.

HOMER P. CHANDLER.
